(57) **CLAIM**

The ornamental design for a furniture unit, as shown and described.

DESCRIPTION

FIG. 1 is a perspective view of a furniture unit, showing our new design, with portions thereof broken away;

FIG. 2 is a side elevational view of the furniture unit, with portions thereof broken away;

FIG. 3 is a front elevational view of the furniture unit, with portions thereof broken away; and,

FIG. 4 is a top plan view of the furniture unit, with portions thereof broken away.

The broken-line disclosure in the views is understood to represent portions of the article in which the claimed design is embodied, but which forms no part of the claimed design.

1 Claim, 2 Drawing Sheets
